UNITED STATES PATENT OFFICE.

PAUL SMITH, OF DAYTON, OHIO.

OIL CUP.

Application filed May 11, 1923. Serial No. 638,424.

This invention relates in general to lubricating devices and more particularly to an oil cup of novel design.

It is an object of my invention to provide 5 an oil cup which may be operated by a simple pressure of the thumb on the top of the cap, obviating thereby the necessity of rotating the cap of the cup as has been heretofore the practice.

10 It is further the object of my invention to provide a check valve to prevent the escape of lubricant except as desired.

Other objects of my invention will appear in the accompanying specifications and 15 claim, and will be disclosed in the accompanying drawings in which:

Figure 1 is a central vertical section.

Figure 2 is a top plan view of my device.

Figure 3 is a side elevation of my device.

20 Referring with greater particularity to the drawings my device will be seen to be comprised as follows: A body portion 1 serves as a container for the lubricant. The body is designed in accordance with the usual 25 practice in that it has its stem machined to the hexagon shape to fit a standard size wrench so that it can be connected with a lead or outlet pipe 8. This outlet pipe 8 in turn connects with the mechanism which 30 is to be lubricated and can be bent as shown by valve lines to accommodate the various conditions of vertical oiling.

In the stem of body 1 there is contained 35 the automatic shut off device which consists of a steel ball check valve 5 which, by the activities of spring 6 is held suitably seated in lower shank of body 5.

The novel feature of my device consists 40 primarily in the cover 2 which is provided with a top 3 consisting of a thin piece of flexible spring steel swedged into the cover and having a convexly curved upper surface. This top 3 has a small hole drilled through it for the admission of air at atmospheric 45 pressure.

Directly beneath the hole 7 in the top 3

there is another thin piece of spring steel 4 which is swedged into the same recess of cover 2 as that which receives top 3. The purpose of this second piece of spring steel 50 is that of a baffle designed to keep oil from spashing out through the hole 7.

The operation of my device is as follows:

When the hole 7 of the top 3 is open the oil contained in the body will be under atmospheric pressure. If the operator then places his thumb upon top 3 in such a manner as to cover the opening 7 and then presses downwardly on the top 3 the air within the body will be compressed forcing the oil in the body 1 downwardly, unseating the valve 5, and permitting the oil to reach those parts which are to be lubricated. When the thumb is released top 3 will spring back into its original position, restoring the air within the body to atmospheric pressure, and permitting the valve 5 to again be seated by the compression of spring 6.

I claim—

In combination, in an oil cup of the character described, a cup body, a cover for said body comprising a flexible diaphragm and retaining means for securing the same to said cup body, a centrally disposed aperture in said diaphragm normally maintaining the 75 interior of said body in communication with the outside atmosphere, said aperture being of such restricted diameter as to adapt the same to be closed by the thumb of the operator, a valve adapted to be seated in the 80 lower portion of said cup body to control the passage of oil therefrom, said valve being adapted to be unseated when the aperture is closed and downward pressure is exerted on said diaphragm, and to be seated when said aperture is opened, and a splash plate mounted in said cup body in close proximity to said aperture to present the egress of oil therethrough due to splashing.

In testimony whereof I affix my signature.

PAUL SMITH.
